(57) **CLAIM**

The ornamental design for a concentrated energy ring water gun, as shown and described.

DESCRIPTION

FIG. 1 is a front perspective view of a concentrated energy ring water gun, showing my new design; FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is the claim in condition of use, where the unclaimed user's hand is depicted in broken lines.

The broken lines in the drawings illustrate the portions of the concentrated energy ring water gun, which form no part of the claimed design.
